UNITED STATES PATENT OFFICE

HAROLD T. BATTIN, OF RIDGEWOOD, NEW JERSEY, ASSIGNOR TO MORGAN & WRIGHT,
OF DETROIT, MICHIGAN, A CORPORATION OF MICHIGAN

MANDREL

Application filed September 9, 1930. Serial No. 480,701.

My present invention relates to mandrels and more particularly to an improved sectional mandrel for use in the manufacture of endless tubes from latex or an aqueous dis-

5 persion of rubber.

The most modern way of building tubes such as used in automobile tires is by the use of the latex deposition process wherein the latex is deposited on the outer surface of 10 an annular mandrel and after such deposition the mandrel is withdrawn from the interior of the endless tube through a performed opening in which may be afterwards placed the valve by means of which the inner tube may be inflated. Heretofore such 15 mandrels have been made of sections which necessitated dismantling the mandrel construction in the process of withdrawing the same from the endless tube. This is objectionable, however, in that the operation of 20 reassembling the mandrel is an operation which is laborious and expensive. In my present invention, I have devised a construction of a mandrel which is built up of a plu- 25 rality of arcuate sections readily assembled together to form an endless annular mandrel and which parts may be readily locked together to form a rigid structure.

The object of my invention, therefore, is 30 an improved endless mandrel.

In the accompanying drawings illustrating the preferred embodiment of my invention:

Figure 1 is an elevation;

35 Fig. 2 is a section on the line 2—2 of Fig. 1;

Fig. 3 is a section on the line 3—3 of Fig. 2; and

40 Fig. 4 is a vertical section of the bottom of the mandrel illustrated in Fig. 1.

Referring to the drawings, 10 and 11 designate arcuate members substantially circular in cross section and semi-circular in form. Such members 10 and 11 are hollow 45 and throughout their surfaces are provided with passages 12 extending from the interior to the exterior thereof. The outer surface of both arcuate members 10 and 11 are knurled as indicated at 13 in Fig. 1, 50 such knurling forming a network of shal-

low grooves over the entire surface of the arcuate members and this network of grooves communicates with the perforations 12.

In the upper end of the arcuate member 10, as viewed in the drawings, is fitted a sleeve 14, this sleeve being held into position relative to the member 10 by a pin 15. Extending transversely of and being anchored in the sleeve 14 is a rod or shaft 16 on which is rotatably mounted a sleeve 17 having formed integrally therewith a member 18. This member 18 has the outer end thereof threaded as indicated at 19 and associated with such threaded end is a nut 20. Slidably mounted in the outer end of the sleeve 14 is a plug 21 provided with a groove 15a which cooperates with the pin 15, the outer peripheral edge of which is rounded as indicated at 22 for a purpose to be hereinafter described. Formed integral with the plug 21 and on the outer end thereof is a cylindrical portion 23 and this cylindrical portion is counterbored to form a chamber 24. The plug 21 is provided with a longitudinal perforation through which extends the member 18 and the nut 20 screwing on the threads 19 forces the plug 21 into the sleeve 14 and brings the rounded peripheral edge 22 of such plug into intimate engagement with the open end of the sleeve 14 which covers the arcuate member 10. The perforations 12 in the arcuate member 10 in that portion of the member occupied by the sleeve 14 are extended through the sleeve 14 so that the said perforations communicate with the interior of the sleeve 14.

Secured in the open end of the arcuate member 10 by pin 25 is a sleeve 26 and extending transversely of the sleeve and having its ends resting therein is a rod or shaft 27. Rotatably mounted on the rod 27 is a sleeve 28 which has formed integral therewith a rod or shaft 29, the outer end of this rod being threaded as indicated at 30. Associated with the threaded end 30 is a nut 31. Fitting into the open end of the sleeve 26 and prevented from rotary movement with respect thereto by a pin 32 engaging in a slot 33 in the sleeve 26 is a cylindrical mem- 100

ber 34. This cylindrical member is provided with a perforation through which extends the rod or shaft 29 and the nut 31 holds the sleeve 34 in position in the sleeve 26. The 5 outer peripheral edge of the cylinder member 34 is rounded as indicated at 35 to engage the outer edge of the arcuate member 11 for a purpose to be hereinafter described. The sleeve 34 is counterbored as indicated at 10 36 to fit over the cylindrical member 23 of the plug 21. The perforations 12 in that portion of the arcuate member 11 occupied by the sleeve 26 are continued through such sleeve 26 so that the interior of the sleeve 15 26 communicates with the outer surface of the arcuate member 11. The plug 21 and cylindrical member 34 are drilled longitudinally at a plurality of points as indicated by the numeral 37 to provide a passage between the arcuate members 10 and 11.

When the cylindrical member 34 is fitted over the cylindrical portion 23 of the plug 21, as indicated in Fig. 3, the walls of the cylindrical member 34 and member 23 are 20 drilled to receive a taper plug 38, and the wall of the cylindrical member 34 is threaded as indicated at 39 to receive the threaded end 40 of such taper plug 38. The arcuate member 11 surrounding the outer portion of the tapered member 38 is recessed as indicated at 41 to provide a chamber in which fits a hollow ring 42 for a purpose to be hereinafter described. The taper plug 38 is drilled longitudinally, and the outer end 25 35 thereof is provided with a plurality of grooves 43 which assist in holding a flexible conduit to such taper plug 38 and through which conduit a source of vacuum or pressure may be attached. Intermediate the groove 43 and the taper portion of the taper plug 38 is provided a member 44, and by means of which the taper plug 38 may be rotated to either lock the arcuate members 10 and 11 together, as indicated at Fig. 3 30 or allow such members to be separated from each other, or to support said members 10 and 11 without touching the latex deposit on said members.

In the lower open end of the arcuate member 10 is fitted a sleeve 46, this sleeve being held in position by a pin 47. Extending transversely of the sleeve 46 is a rod or shaft 48 on which is rotatably mounted a sleeve 49. Formed integral with such sleeve 49 is an 50 55 outwardly extending rod or shaft 50. The outer end of such shaft is threaded as indicated at 51 to receive a nut 52. That portion of the arcuate member 10 occupied by the sleeve 46 has the perforations 12 at such portions extending through the sleeve 46 as above described for the sleeves 14 and 26. Slidably mounted in the open end of the sleeve 46 is a plug 53, this plug being provided with a groove 54 in which fits a pin 55 carried by the sleeve 46 and which allows

movement of the plug 53 while preventing rotative movement thereof.

The outer peripheral edge of the plug 53 is rounded at 56 for a purpose to be herein-after described. Also, the plug 53 is pro- 70 vided with a centrally located perforation through which extends the member 50 and which member, together with the nut 52, holds the plug 53 in position in the sleeve 10. The outer central portion of the plug 53 is 75 counterbored to receive as a sliding fit a portion of a cylindrical collar 58, which may, if desired, be maintained in such counterbored portion and held against rotation or removal by a pin 59. The open end of the arcuate 80 member 11 is fitted with a sleeve and plug corresponding in construction to the sleeve and plug 46 and 53, respectively, and as these constructions are identical the construction for the open end of the arcuate 85 member 11 will not be described in detail. Fitting over each of the arcuate members 10 and 11 is a fabric sleeve 60 and the ends of the sleeve 60 on the arcuate member 10 are brought inwardly and right between the inner outer surface of the sleeve 14 and the rounded portion 22 of the plug 21 and between the inner surface of the sleeve 46 and the outer rounded surface 56 of the plug 53 and such rounded portions 22 and 56 serve 90 to hold the sleeve 60 in position. Similarly the fabric sleeve 60 on the arcuate member 11 has its ends held in position by the rounded end 35 of the cylindrical member 34 and the sleeve and plug located in the lower open 95 end of such arcuate member. The portion of the fabric sleeve 60 surrounding the taper plug 38 is forced into the recess 41 and is held in such recess by the ring 42.

Assuming that the device has been constructed and assembled as above described and that it is desired to form an endless latex tube thereon, and remove the mandrel from the inside of such tube a conduit (not shown) is attached to the groove portion 43 of the taper plug 38 and vacuum applied to the interior of the arcuate members 10 and 11. The entire construction is then dipped into a bath of powdered chalk or whiting and a layer of such chalk or whiting is deposited on the outer surface of the fabric sleeves 60. The structure is then removed from such bath and the coating of whiting or powdered chalk allowed to dry, this coating forming a filter bed for the sub- 105 sequent operation. After drying and with the vacuum still applied to the tapered plug 38 the entire structure is placed in a latex bath, whereupon such latex is deposited on the fabric sleeve 60. After the deposit has 110 acquired the proper thickness, the entire structure is removed from the bath and allowed to dry with preferably the vacuum still being applied to the taper plug 38. After drying, the source 115 120 125 130 135

of vacuum may be removed from the tapered plug 38 and the latex endless tube is vulcanized. After vulcanization, the tapered plug 38 is removed from the position shown in Fig. 3 and the operator will slide the cylindrical portion 23 from the cylindrical chamber 36 and the preformed hole in the endless tube formed of necessity by the presence of the tapered plug 38 is distended and slid over the outer end of the arcuate member 11. The construction of the cylindrical sleeve 58 and the counterbored portions in the sleeves 46 in the lower ends of the arcuate members 10 and 11 is such as to permit a separating movement of the arcuate members 10 and 11, with respect to each other, while still maintaining the same in vertical alignment. The mandrel composed of the arcuate members 10 and 11 may now be readily fed through the valve hole in the endless latex tube and to facilitate this operation, it is preferable to insert the end of an air hose between the endless tube and the outer surface of the fabric sleeves 60. The introduction of air through such air hose will inflate the endless latex tube and it will be found that the mandrel may be readily removed from the inside of the endless latex tube. During all this time, the arcuate members 10 and 11 may either be maintained in physical contact with each other or removed separately and after removal from the endless latex tube may be readily reassembled to have the sequence of operations above described repeated thereon.

When the plug 38 is in place locking the two halves together, the mandrel halves can not separate at the lower joint because they could not move along a line parallel to the surface of collar 58 without bending the tube (because of its circular shape), thereby causing pinching between collar 58 and plug 53 in member 11.

Having thus described my invention what I claim and desire to protect by Letters Patent is:

1. In an improved mandrel, the combination of a plurality of hollow arcuate members assembled to form a rigid annulus, shells fitting into the open end of adjacent arcuate members, male and female locking members removably mounted in the shells, and a locking bolt cooperating with the male and female locking members for locking adjacent ends of the arcuate members together.

2. An endless mandrel comprising a plurality of separable curved sections, shells fitting into the adjacent ends of said sections, pivotally mounted supporting bolts carried by said shells, telescoping ring members carried by said supporting bolts, and means for locking said sections and members together.

3. An endless mandrel comprising a plurality of curved sections, a covering of tubular fabric for said sections, the ends of said fabric extending into a pair of adjacent ends of said sections, and means in said adjacent ends of the sections for fastening said ends of the fabric in place. 70

4. An endless mandrel comprising a plurality of curved sections, a covering of tubular fabric for said sections, the ends of said fabric extending into a pair of adjacent ends of said sections, and clamping rings for said fabric ends for securing them within the mandrel. 75

5. An endless mandrel comprising a plurality of curved sections, a covering of tubular fabric for said sections, the ends of said fabric extending into a pair of adjacent ends of said sections, and clamping rings for said fabric ends for securing them within the mandrel, said rings and adjacent ends of said sections having complementary curved clamping surfaces. 80 85
